US0D1072588S

(12) **United States Design Patent** (10) **Patent No.:** **US D1,072,588 S**
(45) **Date of Patent:** **** Apr. 29, 2025**

(54) **BLENDER**

(71) Applicant: **NUC ELECTRONICS CO., LTD.**,
Daegu (KR)

(72) Inventor: **Jong Boo Kim**, Daegu (KR)

(73) Assignee: **NUC ELECTRONICS CO., LTD.**,
Daegu (KR)

(**) Term: **15 Years**

(21) Appl. No.: **35/518,683**

(22) Filed: **Oct. 18, 2022**

(80) **Hague Agreement Data**

Int. Filing Date: **Oct. 18, 2022**

Int. Reg. No.: **DM/225043**

Int. Reg. Date: **Oct. 18, 2022**

Int. Reg. Pub. Date: **Oct. 20, 2023**

(30) **Foreign Application Priority Data**

May 12, 2022 (KR) 30-2022-0018962

(51) **LOC (15) Cl.** **07-04**

(52) **U.S. Cl.**
